CLAIM

The ornamental design for a printer, as shown and described.

DESCRIPTION

FIG. 1 is a top, rear and right side perspective view of a printer showing my new design;

FIG. 2 is a front elevational view thereof;

FIG. 3 is a top plan view thereof;

FIG. 4 is a bottom plan view thereof;

FIG. 5 is a left side elevational view thereof; and,

FIG. 6 is a cross-sectional view thereof taken along line VI-VI of FIG. 2 and a portion defined by an arrow VI' of FIG. 5.

The broken lines shown in FIG. 6 illustrate portions of the printer that form no part of the claimed design.

The dash-dot broken lines in FIG. 6 represent the boundary lines of the partially enlarged range and form no part of the claimed design.

The present article is a printer for receiving image data from an electronic device or the like via wireless communication, to print an image on an instant film according to the received image data. The instant film after printing is delivered out of an exit slot in a top of a body.

1 Claim, 5 Drawing Sheets
